UNITED STATES PATENT OFFICE.

ERNEST M. SKINNER, OF DORCHESTER, MASSACHUSETTS.

ORGAN.

No. 807,510.

Specification of Letters Patent.

Patented Dec. 19, 1905.

Application filed November 4, 1902. Serial No 130,071.

To all whom it may concern:

Be it known that I, ERNEST M. SKINNER, a citizen of the United States, residing at Dorchester, in the county of Suffolk and State of Massachusetts, have invented new and useful Improvements in Organs, of which the following is a specification.

This invention relates to organs, and has for its object to increase the combination possibilities of stops belonging to different manuals without the use of couplers.

To this end my invention consists in the features and in the combination, construction, and arrangement of parts hereinafter described, and particularly pointed out in the claims following the description, reference being had to the accompanying drawings, forming a part of this specification, wherein—

20 Figure 1 is a diagrammatic view, partially in section, illustrating my invention. Fig. 2 is a vertical sectional view illustrating the valve mechanism controlling one of the organ-pipes of one of the stops. Fig. 3 is a side 25 elevation of the parts shown in Fig. 2. Figs. 4 and 5 are respectively sectional views illustrating the automatic duplex or double-acting valve in its two different positions.

In organs as heretofore constructed it has 30 been customary to provide mechanical coupling devices whereby when a register has been drawn out and one of the keys of the organ—say, for example, one of the keys of the swell-manual—be struck the corresponding key in 35 the great-organ manual will be enabled to sound the same note in such stop. By means 40 of the improved mechanism which I am about to describe I am enabled to sound a note on any one of the stops or on any combination 45 of stops from either the swell-manual or the great-organ manual and am also enabled to simultaneously sound a note on one combination of stops from the swell-manual and another combination of stops from the great- 50 organ manual without regard to which manual the stops normally belong.

Referring to the drawings, the numeral 1 indicates a wind-chest which is constantly supplied with compressed air. Comprised with 55 or forming a part of said chest is a series of stops 3, 4, 5, and 6, each consisting of a plurality of organ-pipes, it being assumed in the present instance that each stop comprises sixty-one different pipes adapted to sound a corresponding number of different notes. I have illustrated but four different stops in the

drawings; but it will of course be understood that any desired number of stops may be provided. For the purpose of illustration it will be assumed that the stop 3 is the flute, stop 4 the dulciana, stop 5 the stopped diapason, and the stop 6 the salicional. The pipes in each of said stops communicate at their lower ends with air-ports 7, which extend through the top of the wind-chest 1, and all of the ports 60 corresponding to each stop communicate with air-passages 8, that are formed in vertical partitions 9, arranged parallel with one another in the wind-chest. Said passages 8 at their lower ends are deflected horizontally, as 65 indicated at 8', the ends of the horizontal portion of said passages being controlled by valves 10. Each valve 10 is mounted on the upper end of a lever 11, which is pivoted intermediate its ends, as at 12, to the partition 70 75 9, the lower end of said lever being connected to a flexible diaphragm 13, as indicated at 14, said diaphragm being arranged in a circular mortise 15, formed in one side of the partition. The valve 10 is normally held to 80 its seat over the end of the passage 8' by a spring 16.

It will of course be understood by those skilled in the art that there will be one such valve as above described for each note in 85 each stop. As before stated, the wind-chest 1 is constantly supplied with air under pressure, and the partitions 9 extend across the wind-chest, as is most clearly shown in Fig. 1 of the drawings, the air-pressure being admitted from a wind-conductor (not shown) extending across the end of said wind-chest and common to all of said valves. It will be obvious, therefore, that if one of the valves 10 be opened the compressed air in the wind-chest will be permitted to escape through the 90 passage 8 and into and out of the organ-pipe corresponding thereto and will cause said pipe to speak.

Leading from the chamber 15 is a channel 100 17, that communicates at its lower end with an air-duct 18, formed transversely in the partition 9, and loosely mounted in said air-duct is the stem 19 of a duplex valve, said stem being provided at its opposite ends, respectively, with disks 20 and 21, which constitute valves adapted to close the opposite ends of the air-duct 18, the length of the stem 19 being such that one of said valves may be closed at a time—that is to say, when the valve 21, 105 for example, as shown in Fig. 1, is in a position to close the corresponding end of the

air-duct the valve 20 will be unseated and will therefore open the adjacent end of the air-duct. Arranged on opposite sides of the partition 9 of each stop are stop-chambers 22 and 23, each of which is common to all the sixty-one notes or organ-pipes included in such stop. Said stop-chambers are normally supplied with air under pressure from the bellows (not shown) and through ports 24 and 25, respectively, communicate with air-passages 26 and 27, said ports being adapted to be cut off by puppet-valves 28 and 29, as hereinafter described. The passages 26 and 27 communicate with the channel 17 through the medium of the air-duct 18^a and through the medium of passages 26^a and 27^a, respectively, communicate with channels 30 and 31, which are common to the same note of all the stops—that is to say, there will be one set of such channels 30 and 31 for each note of all the stops. For example, the channels 30 and 31 are common to the note C in the flute, dulciana, stopped diapason, and salicional stops. One of the channels—as 30, for example—will be controlled from the great-organ manual, and the other channel 31 will be controlled from the swell-manual, as will more fully be hereinafter explained.

The numeral 32 indicates a pneumatic that communicates by an air-passage 33 with the channel 30. Said pneumatic is provided with a port 34, that opens to the atmosphere, and said port is controlled by a valve 35, that is mounted on a stem 36, said stem being connected to a flexible diaphragm 37, which is disposed in a chamber 38, formed in said pneumatic. The pneumatic is normally supplied with compressed air from the organ-bellows and operates to hold the valve 35 closed against the port 34, whereby the channel 30 will normally be filled with compressed air. The chamber 38 of the pneumatic 32 communicates by a passage 39 with a pneumatic 40, said pneumatic being provided with a port 41, opening to the atmosphere, said port being controlled by a valve 42, that is carried by an armature 43. The said armature is arranged opposite the poles of an electromagnet 44, which is mounted within the pneumatic 40. The pneumatic 40 is normally supplied with compressed air from the organ-bellows, whereby the valve 42 is normally held closed against the port 41. The pneumatics 40 and 32 are of well-known construction, and the specific construction shown forms no part of the present invention. Communicating with the stop-chamber 22 by means of a pipe 44' is a pneumatic 45, provided with a port 46, opening to the atmosphere, said port being controlled by a valve 47, the stem of which is connected to a flexible diaphragm 48. The space behind the diaphragm 48 is connected by a passage 49 with a pneumatic 50, identical in construction with the pneumatic 40 before referred to, the valve 51 of

said pneumatic being controlled by an electromagnet 52. The stop-chamber 23 communicates with a pneumatic 53, which is controlled by a pneumatic 54, the valve in said last-mentioned pneumatic being operated by an electromagnet 55, the construction and arrangement of the pneumatics 53 and 54 being identical in construction with and corresponding in arrangement to the pneumatics 45 and 50 described.

The numeral 56 indicates an electric battery, and numerals 57 and 58, respectively, indicate the keys of the swell and great organ manuals, each of said keys being adapted to close the terminals of an electric circuit. For the purpose of illustration I have shown two contacts 59 and 60 arranged adjacent to the inner end of each of the keys, said contacts when the corresponding key is depressed being bridged by a metallic strip 61, attached to the inner end of such key. The contact 60 of the great-organ key 58 is connected by a wire 62 to the positive pole of the battery, and the adjacent contact 59 is connected by the wire 64 to one terminal of the electromagnet 44, the other terminal of said magnet being connected by the wire 65 with the negative pole of the battery. It will be obvious, therefore, that if a key 58 of the great-organ manual be depressed the circuit will be closed through the contacts 59 and 60, thus energizing the magnet 44, which will then operate to attract its armature 43 and withdraw the valve 42 from the port 41. The air will thus be drained from behind the diaphragm 37, and the pressure of air within the pneumatic 32 will force said diaphragm to the left, withdrawing the valve 35 from the port 34, thereby putting the channel 30 in communication with the atmosphere.

One terminal of the electromagnet 52 is connected by a wire 63 to one member 67 of a circuit-closer, the other member 68 of said circuit-closer being connected by the wire 69 to the positive pole of the battery. The other terminal of said electromagnet 52 is connected to the wire 65, leading to the negative pole of the battery. The terminals 67 and 68 are adapted to be closed by a register 71, which is provided with a shank 72, formed of insulating material and having fixed to its end a metallic head 74, so that when the register 71 is drawn out the metallic head 74 will engage both the contacts 67 and 68 and close the circuit. When the circuit is closed, the magnet 52 will be energized, thereby withdrawing the valve 51 away from the port 49 and putting the chamber behind the diaphragm 48 in communication with the atmosphere through said port 49, thus drawing the valve 47 away from the port 46 and putting the stop-chamber 22 into communication with the atmosphere through the pipe 44' and port 46.

Let it now be assumed that the register 71 has been drawn out to close the circuit through

the electromagnet 52. When this has been done, the stop-chamber 22 will be drained—that is to say, will be in communication with the atmosphere in the manner before described. The pressure in the channel 30 will now operate to throw the valve 28 to the left, thus putting the passages 26 and 26^a in communication. If a key 58 on the great-organ manual be now struck, it will close the circuit through the contacts 59 and 60, thereby energizing the magnet 44, which will place the channel 30 in communication with the atmosphere in the manner before described, whereupon the air on the left of the diaphragm 13 will be vented through passages 17, 18, 26, 26^a, and 30. The wind-chest 1 being filled with compressed air, the preponderance of pressure will operate upon the flexible diaphragm 13 to move the valve 10 away from its seat, thus causing the organ-pipe 3 to speak. The operation of pneumatic 13 is not affected by the air in stop-chamber 23, as the compressed air in said stop-chamber 23 operates to force the valve 25 to its seat against the adjacent end of the air-duct 27 and will also force the valve 21 laterally to one side, closing the communication with the port 17. If it be desired to cause the same note in the same stop to speak from the swell-manual, it is merely necessary to depress the key 57 of the swell-manual, thereby bridging the contacts 59 and 60 adjacent to the inner end of said key, it being assumed, of course, that the stop 80 has been drawn out to put the swell-manual into communication with the flute-stop by venting the stop-chamber 23. When this has been done and the key 57 has been depressed, the circuit will be completed from the positive pole of the battery through the wire 65 and contacts 59, 60, and 61 and the wire 76 to the electromagnet 83, which is arranged in the pneumatic 84 and constructed identically like the pneumatic 40, previously described. This pneumatic will control a pneumatic 85, corresponding to the pneumatic 32 on the great-organ manual. The depression of the key 57 will thus place the channel 31 in communication with the atmosphere. The register 80, however, being pulled out, a portion of the current will be diverted by wire 88 to and through the register 80 and by wire 89 to the electromagnet 55 in the pneumatic 54 and by the common return-wire 65 to the negative pole of the battery. The magnet 55 will then open the valve 54, and thus place the stop-chamber 23 in communication with the atmosphere through the pneumatic 53, whereupon the preponderance of pressure in the wind-chest 1 will cause the diaphragm 13 to collapse, thereby opening the valve 10 and sounding the note in the flute-stop 3. It will thus be seen that the note on the flute-stop 3 may be played from either the swell-manual or the great-organ manual without the employment of a coupler, it be-

ing merely necessary to draw out the proper registers to place either manual in communication with the flute-stop and strike the key.

I have described merely the relation between the pneumatics and one stop; but it will of course be evident by referring to Fig. 1 of the drawings that each stop is provided with a set or series of pneumatics arranged to operate in the manner hereinbefore described and that by pulling out either one of the registers shown in said figure of the drawings a corresponding stop will be operably connected with the manuals. For example, by pulling out the stops 71 and 86 any one of the keys of the great-organ manual will be enabled to cause a note to simultaneously sound on the flute-stop 3 and the dulciana-stop 4, and if the stop 80 be drawn out and the stop 87 be also drawn out and a key be struck upon the swell-manual a note will be sounded that will combine the flute and salicional stops. By the proper manipulation of the stops the combination that may be formed or grouped together is almost infinite, and these combinations may be effected with relation to either the swell-manual or the great-organ manual at will. For example, by drawing out the proper registers the flute and salicional stops may be played from the swell-manual and the flute and stopped diapason may be played from the great-organ manual. In other words, by the arrangement shown and described any one or all the stops may be played from the swell-manual and from the great-organ manual, or separate combinations may be played from one manual and another separate and distinct combination of stops may be played from the other manual.

Having described my invention, what I claim is—

1. In an organ the combination of a wind-chest, a pneumatic valve arranged therein and controlling one of the organ-pipes, a wind-way controlling said valve, two outlets for said windway, a duplex valve and puppet-valves controlling said outlets, and a channel for each of said outlets, substantially as described.

2. In a pipe or reed organ, a single set of pipes or reeds, and a single set of pneumatically-actuated valves having diaphragms connected therewith combined with channels in the bottom board and duplicate-stop wind-chambers, adapted to be vented by draw-stops, and valves, channels and a duplex valve, for automatically establishing communication between the valve-actuating diaphragm and channel in the bottom board, when a stop is on and a key depressed.

3. In a pipe or reed organ, in combination, a stop rib or bar, having a wind-passage, leading from the wind-chest to the pipe or reed, a pivoted valve-lever, a diaphragm-chamber in said rib or bar, a flexible diaphragm covering such chamber, and connected to the

lower end of the valve-lever, a passage leading from the diaphragm-chamber, a conduit in open communication with said passage, a duplex valve arranged in the said conduit,
5 passages communicating with opposite ends of the said conduit, channels in the bottom board, wind-chambers having openings, and puppet-valves, and openings, leading from the passages to the channels in the bottom board.
10 4. In a pipe or reed organ, a pipe or reed, duplicate-stop wind-chambers adapted to be vented by draw-stops, separate air-channels from both of which the pipe may be sounded, valve-controlled passages between the stop
15 wind-chambers and said separate air-channels,

a diaphragm-chamber, a lever carrying a pneumatically-actuated valve for controlling the passage of air to the pipe and operatively connected with the diaphragm of the diaphragm-chamber, and an automatically-operated valve controlling connection between the diaphragm-chamber and the separate air-channels from which the pipe may be sounded. 20

In testimony whereof I have hereunto set my hand in presence of two subscribing witnesses. 25

ERNEST M. SKINNER.
